UNITED STATES PATENT OFFICE.

WILLIAM C. LIKLY AND JOHN J. CANNAN, OF ROCHESTER, NEW YORK, AS-SIGNORS TO HENRY LIKLY & COMPANY, OF ROCHESTER, NEW YORK, A CORPORATION OF NEW YORK.

WARDROBE-TRUNK.

No. 849,334.

Specification of Letters Patent.

Patented April 2, 1907.

Original application filed May 14, 1906, Serial No. 316,626. Divided and this application filed November 28, 1906. Serial No. 345,262.

To all whom it may concern:

Be it known that we, WILLIAM C. LIKLY and JOHN J. CANNAN, both of Rochester, in the county of Monroe and State of New York, have invented certain new and useful Improvements in Wardrobe-Trunks; and we do hereby declare the following to be a full, clear, and exact description of the same, reference being had to the accompanying drawings, forming a part of the specification, and to the reference-numerals marked thereon.

Our present invention relates to trunks, and particularly to the type known as "wardrobe-trunks," which are intended to stand on end in a vertical rather than a horizontal position to preserve the shape and position of garments and other articles contained therein, whereby the necessity of packing the contents closely is avoided; and it has for its object to provide such a trunk having a removable cabinet divided into compartments adapted to receive the smaller articles of clothing and those accessories usually carried by travelers, which is detachably mounted upon the hinged side or cover of the trunk and fits within the body or wardrobe-compartment when the parts of the trunk are closed.

To these and other ends the invention consists in certain improvements and combinations of parts, all as will be hereinafter more fully described, the novel features being pointed out in the claims at the end of the specification.

In the drawings, Figure 1 is a front elevation of a trunk constructed in accordance with our invention, showing the cover or door in open position and the handle portion in section. Fig. 2 is a vertical sectional view on the line 2^x 2^x of Fig. 1, but with the cover or door closed. Fig. 3 is a detail horizontal sectional view taken on the line 3^x 3^x of Fig. 2.

Similar reference-numerals in the several figures indicate similar parts.

The present invention is a division of the one shown and described in our prior application, Serial No. 316,626, filed May 14, 1906, and in order to illustrate it we have shown a trunk of the usual construction consisting of

the rectangular box or body, having a top 1, a bottom 2, a back 3, and the two sides 4 4. Hinged at one side of the box or body is a door or cover, comprising a panel 5, sides 6 6, 55 and ends 7 7, which latter are adapted to cooperate with the corresponding sides and ends of the box or body and when closed thereon to be secured by the usual or any preferred construction of locking devices, 60 which have been omitted from the illustrations. The trunk is adapted to rest upon its lower end 2, which is provided with casters or rollers 8 to facilitate its being moved when supported in the normal position, and a similar roller 8' is provided on the corresponding end of the cover, as shown in Figs. 1 and 2.

On each end of the trunk are the handles by means of which it may be carried. The one located on the lower end 2 of the body 70 (omitted from the illustrations) may be of the usual construction and is adapted to lie flat, so that it will not engage the floor when the trunk stands in the normal upright position on the casters. The other handle, arranged on the upper end or top 1 of the body, 75 forms a projection intended to prevent the trunk from being stood in an inverted position, and it comprises end posts 10, preferably made of sheet metal having rounded ends 80 and flat bases, which latter are secured by rivets 11 to the top of the trunk. In the adjacent sides of the rounded ends of each post are apertures receiving the ends of a revolvable tubular cross-piece 12, which may be provided with a covering of leather or other suitable material. By forming a handle at one end of the trunk in the manner described, the parts may be made sufficiently strong to serve the purpose for which they are intended without adding materially to the weight of the trunk. The bar or cross-piece 12 may be rigidly connected to the posts or formed integral therewith; but if it is free to rotate it forms a more convenient grip-piece, 95 as will be understood, and being located beneath the outer ends of the posts it is protected from injury.

The box or body of the trunk forms a chamber in which garments or other articles 100 may be packed, and to enable it to be utilized as a wardrobe-compartment wherein

garments may be hung it is provided with an extensible supporting-frame 13, guided in channels formed in the proximate faces of ways or strips 14, secured to the sides 4 4 of the trunk-body and projecting inwardly therefrom in proximity to the top 1. A plurality of garment-hangers 150 depend from the frame 13, and the garments suspended thereon may be compressed and secured within the trunk by a suitable follower of the usual or any preferred construction, as will be understood.

The means we have provided for carrying the smaller pieces of clothing, toilet accessories, and other articles comprises a cabinet-section removably fitted within the trunk beneath the supporting-frame 13 and its ways 14 and capable of being detached therefrom and used in lieu of a chiffonnier or dresser, thus permitting the entire box of the trunk to be utilized as a wardrobe. In illustrating our invention we have shown a cabinet comprising side pieces 15, between which are provided a plurality of compartments of any desired size and arrangement, which are closed at their rear sides by a back 16 and are accessible from their forward sides through the doors or flaps 17. Each of the side walls of the cabinet-section is provided near its upper end with a block or member 18, having a downwardly-extending finger or projection 19, which engages with a correspondingly hook-shaped projection 20 on a block 21, secured to the side walls 6 and the back 5 of the cover. These blocks form interlocking members which support the cabinet-section with its lower end or bottom 22 slightly above the plane of the end or bottom walls 2 and 7 of the trunk-box and cover, respectively, permitting the weight of the cabinet and its contents to hold the interlocking members tightly in engagement. The bottom of the cabinet is retained in position by a transversely-extending strip 23 thereon, which engages in rear of a similar strip or cleat 24, secured to the corresponding end 7 of the trunk-cover, as shown in Fig. 2. The cabinet-section is made of less width than the corresponding internal dimension of the trunk, so that it may be made of a greater depth than the cover, and when carried thereon may be rotated into the open side of the body to occupy the space afforded therein beneath the supporting-frame when the contents of the wardrobe-compartment have been compressed. To hold the section in central position in the trunk, its side walls are provided with the vertically-extending spacing-strips 25. When the cover is closed, the ways 14 project over the lateral edges of the top 26 of the cabinet and prevent endwise movement thereof sufficient to disengage the interlocking projections when the trunk is being transported.

65 By providing the removable cabinet-sec-

tion the trunk is adapted either for personal use or to be employed as a sample-trunk and adapting it to enter the body. The space which would otherwise be vacant when the follower or compressor is moved inwardly is utilized. 70

We claim as our invention—

1. In a trunk, the combination with a body portion open at one side, of a cover for closing it, a cabinet-section removably supported on the cover and adapted to project into the 75 body of the trunk when the cover is in the closed position.

2. In a trunk, the combination with a body open at one side and a cover for closing it comprising shallow side and end walls and a 80 back, of a cabinet-section arranged therein and adapted to project into the body of the trunk comprising side walls and of less width than the cover and body, members spacing the cabinet-section centrally of the cover and 85 interlocking devices on the cabinet and cover removably securing the former within the latter.

3. In a trunk, the combination with a body open at one side, guides projecting outwardly 90 beyond the edges of the body at one end thereof and a frame supported in the guides and having an edge also projecting beyond the edges of the body, of a cover fitted to the outer side of the latter and comprising a back 95 and side and end walls of a depth to receive the projecting ends of the guides and the edge of the frame and a cabinet-section mounted on the cover and projecting into the body of the trunk when said cover is closed. 100

4. In a trunk, the combination with a body open at one side and a cover fitted thereto, both the body and cover comprising side and end walls and a back, of a cabinet-section arranged within the trunk body and cover having side walls, spacing members on the cabinet supporting it centrally between the side walls of the trunk and coöperating interlocking members on the cabinet and cover arranged in rear of the spacing members and 110 detachably supporting the cabinet on the cover.

5. In a trunk, the combination with a body open at one side and a cover fitted thereto, of a cabinet-section fitting the interior of the 115 trunk, detachable connections between the cabinet and cover and garment-supporting devices arranged within the trunk and adapted to prevent the disengagement of the connections when the cover is closed. 120

6. In a trunk, the combination with a body open at one side and a cover therefor, a cabinet-section fitting the trunk and detachable connections between it and the cover, of garment-supporting devices arranged within the 125 trunk-body and coöperating with the top of the cabinet to prevent its longitudinal movement when the cover is closed.

7. In a trunk, the combination with a body open at one side, a cover hinged to the body 130

and a cabinet-section supported on the cover and projecting into the body and having its top spaced a fixed distance from the top of the trunk, of detachable connections between the cabinet and cover, garment-supporting devices arranged in the top of the trunk comprising a movable frame and relatively stationary guides adapted to project over the

top of the cabinet when the parts are in the normal position.
